Sacramento, Calif. 95821

Filed Sept. 27, 1965, Ser. No. 87,161

Term of patent 14 years

(Cl. D15—8)

FIG. 1

FIG. 2

FIG-3

FIG-4

FIGURE 1 is a front perspective view of a combined foldable chair and ottoman, showing my new design; FIGURE 2 is a rear perspective view thereof;

FIGURE 3 is a front perspective view illustrating the appearance of the device in ottoman position with the back of the chair folded into the chamber beneath the cushion, with the cushion centered over the chamber and the legs crossed to lower the elevation of the cushion to conventional ottoman height; and

FIGURE 4 is a rear perspective view of FIGURE 3 showing the cushion tab locked to the turn clasp.

I claim:

The ornamental design for a combined foldable chair and ottoman, as shown and described.
